UNITED STATES PATENT OFFICE.

JAMES FRANCIS BARTLETT, OF CLEVELAND, OHIO.

BUCKLE.

SPECIFICATION forming part of Letters Patent No. 365,226, dated June 21, 1887.

Application filed October 1, 1886. Serial No. 215,094. (No model.)

To all whom it may concern:

Be it known that I, JAMES FRANCIS BARTLETT, a citizen of the United States, residing at Cleveland, in the county of Cuyahoga and State of Ohio, have invented certain new and useful Improvements in Buckles; and I do hereby declare the following to be a full, clear, and exact description of the invention, such as will enable others skilled in the art to which it appertains to make and use the same.

This invention relates to buckles for harness or trace fastenings.

Heretofore in harnesses the most usual method of lengthening or shortening the traces or tugs has been by the employment of an ordinary buckle placed at that portion of the harness which would be at or near the neck of the animal in use. A buckle is objectionable here, however, for the reason that, besides being at the neck or shoulders of the animal, and thus likely to gall him, it is in a position to rub against or be rubbed by the tongue or shafts of the vehicle, and thus injure both the buckle and the tongue or shaft. Furthermore, the buckle most commonly used is the ordinary buckle, which cannot be adjusted quickly to lengthen and shorten the trace. Furthermore, traces have generally been attached to the vehicle by inserting the ends of whiffle-trees into slots or openings in the ends of the traces, so that when such an opening was worn or torn out the entire trace had often to be discarded. Where buckles have been used at the rear portion of the traces, and have consisted of a plate having loops at the ends, the plate has either been curved or, in an instance where the plate was flat, the loops have been of different heights, and in both instances adding to the difficulty and cost of construction, particularly in casting, and in the last instance increasing the liability of the whole buckle to interference with other parts, and to injury by having one portion project more than another.

The object of the present invention is to produce a buckle—as for a trace-fastening—and so constructed as to be capable of being placed near the whiffle-tree, and also capable of rapid and ready adjustment to change the length of a trace or other strap, rope, or the like.

Furthermore, the object is to produce means for fastening the trace to the whiffle-tree, which

shall be readily replaceable when worn without removal of the trace itself.

With these objects in view my invention resides, essentially, in a buckle having a central stud, pin, or tongue, and keepers at the end, the keepers being loops of substantially the same height and size, but one being cut, curved, or beveled off on the under side of its top from within outward.

Furthermore, the invention resides in a trace-fastening consisting of the described buckle provided with a slot at its rear end, combined with a separate strap or piece having an opening for attachment upon the whiffle-tree.

I have illustrated the invention in the accompanying drawings, in which—

Figure 1 is a plan view of a trace-fastening made in accordance with my invention, showing the plate, the loops, the stud, the trace, and the separate piece for attachment to the whiffle-tree, the trace being broken away to show this. Fig. 2 is a side elevation of the same, but showing one loop canted; and Fig. 3 is a central longitudinal vertical section showing, in addition to what is displayed by Fig. 1, the particular configuration of one of the loops.

In the accompanying drawings, A represents a plate, of metal or other suitable substance, sufficiently strong to withstand the strain, as upon a trace, and provided, preferably near its center, with a stud, pin, or tongue of suitable diameter and length to enter an ordinary hole in a trace and retain the trace against a lateral pull. The plate is also provided, near each end, with loops a' a'' , to inclose a trace and retain it in engagement with the stud, pin, or tongue a , serving as keepers. The loops are of substantially the same height and size, and on their exterior are of substantially the same shape; but it will be observed that one of them, a'' , (the loop which is at the rear end of the plate in use,) is of a different shape inside from that of the loop a' . On the under side of its top plate it is beveled or cut from within outward, and the purpose of this construction is to allow a trace more readily to be inserted, and after insertion to have more play at the rear end for purposes of manipulation of the trace, to remove it and to permit it more gradually to rise over any projection there.

Instead of being cut away or beveled, as described, the loop may be canted inward, for the same purpose.

B represents a strap, of any suitable material, or a piece of leather, preferably of a width and thickness corresponding to the trace, this piece being attached in a suitable slot, a^3 , in the plate A. The piece B has a hole, b, for the reception of the end of the whiffletree, and upon this piece all the draft strain and twist come. When the piece is torn or worn, it may be replaced by another at very small cost and without discarding the trace.

C represents the trace, which may be of any desired size or thickness, and which is provided with the usual holes, c.

It will be seen from an inspection of Fig. 3 that the configuration of the inner portion of the top of the rear loop, a^2 , permits the trace gradually to rise over the thickened portion of the additional strip or piece B, and how play is permitted to the end of the trace to manipulate the same in attachment or detachment lengthening or shortening of the same.

From the construction shown and described it will be clear that the lengthening and short-

ening of a trace or other piece may readily be accomplished by raising it upon the plate between the loops, as by pushing against it outside of the loop a^2 sufficiently to clear the stud a, and then sliding it along to bring this stud into another of the holes.

Having thus fully described my invention, what I claim, and desire to secure by Letters Patent, is—

1. The herein-described buckle, consisting of a metal plate provided with a pin, stud, or tongue, and having loops at either end serving as keepers, one of the loops being beveled or canted, substantially as and for the purpose set forth.

2. In combination with the plate A, having a slot, a^3 , the separate strap B, provided with the opening b, substantially as shown and described.

In testimony whereof I affix my signature in presence of two witnesses.

JAMES FRANCIS BARTLETT.
